UNITED STATES PATENT OFFICE.

GUSTAVE A. KURZ, OF ZANESVILLE, AND HARRY C. SHONTING, OF COLUMBUS, OHIO.

COMBINATION GARMENT.

1,031,719.

Specification of Letters Patent.

Patented July 9, 1912.

Application filed December 20, 1910. Serial No. 598,355.

To all whom it may concern:

Be it known that we, GUSTAVE A. KURZ and HARRY C. SHONTING, citizens of the United States, residing at Zanesville and Columbus, respectively, in the counties of Muskingum and Franklin, respectively, and State of Ohio, have invented certain new and useful Improvements in Combination Garments, of which the following is a specification.

This invention relates to wearing apparel and more particularly to a combination garment embodying in its structure, a coat and trousers.

15 The object of the invention is to provide a combination garment especially designed to be worn by chauffeurs, machinists and other persons, either as a rain-coat, or as a top coat or ulster, and which will effectually 20 protect the under coat and trousers and prevent the latter from becoming soiled, while at the same time permits freedom of movement of the legs of the wearer when kneeling, bending or performing manual labor 25 of various kinds.

A further object is to provide a coat having trousers secured to the inner face thereof and capable of being adjustable vertically of the coat to fit the legs of the wearer.

30 A further object is to provide means whereby the trousers may be folded within the lines of the coat when not in use so as to permit the coat to be used in the ordinary manner.

35 A further object is to provide a coat, the trousers of which are suspended from the inner face thereof by flexible attaching straps so as to form in effect a loose connection between the trousers and coat and thus 40 allow free movement of the legs of the wearer.

Further objects and advantages will appear in the following description, it being understood that various changes in form, 45 proportions and minor details of construction may be resorted to within the scope of the appended claims.

For a full understanding of the invention and the merits thereof, reference is to be 50 had to the following description and accompanying drawings, in which:

Figure 1 is a perspective view of a combination garment constructed in accordance with my invention, showing the manner of 55 using the same; Fig. 2 is a perspective view of one of the trousers legs removed from the

coat, the suspension straps being shown detached from the trousers leg and a portion of the coat, with the fastening devices secured thereto, being also shown in perspective in order to more clearly illustrate the construction of the several parts; Fig. 3 is a rear elevation, partly in section, showing the manner of folding the trousers legs when not in use; Fig. 4 is a perspective view illustrating a modified form of the invention; Fig. 5 is a front elevation, partly in perspective, illustrating a further modification; Fig. 6 is a similar view, showing the manner of folding the trousers leg shown in Fig. 5; Fig. 7 is a vertical sectional view taken on the line 5—5 of Fig. 8 and looking in the direction of the arrow; Fig. 8 is a vertical sectional view taken on the line 8—8 of Fig. 6, and looking in the direction of the arrow.

Corresponding and like parts are referred to in the following description and indicated in all the views of the drawings by the same reference characters.

The improved combination garment forming the subject matter of the present invention comprises a top coat or ulster 5, preferably formed of water proof material and having oppositely disposed side pockets 6. 85 Suspended from the inner face of the coat 5, are detachable trousers legs 7 also preferably formed of water proof material, one of the legs 7 being preferably arranged opposite each pocket 6, as shown. The material at the opposite vertical edges of each leg 7 is overlapped and provided with interengaging fastening devices, preferably consisting of resilient heads 8 secured to one edge of the material and adapted to engage 90 correspondingly shaped sockets 9 secured to the other edge of the material so that the parts may be readily separated and placed in position on the legs of the wearer.

Secured to the inner face of the material comprising each leg 7, at the upper end thereof, is a reinforcing tape 10, to which are detachably secured by interengaging fastening devices 11, flexible suspension straps 12. The intermediate portions of the suspension straps 12, intersect above the adjacent legs 7, while the upper ends of said straps are sewed or otherwise permanently secured to an attaching member 13 formed of canvas, leather or other relatively thick 105 or durable material.

A guiding loop or strap 14 is secured to

- one of the intersecting suspension straps 12 and embraces the mating suspension strap, thus to hold said straps in assembled position, while at the same time permitting one strap to move relative to and independent of the other and thus allow freedom of movement of the legs of the wearer, when bending, kneeling or otherwise performing manual labor.
- 10 Sewed or otherwise secured to the inner face of the coat opposite each pocket 6, is a reinforcing strip 15 having a plurality of vertically disposed rows of fastening devices secured thereto and preferably in the form 15 of resilient heads 16, similar in construction to the heads 8, and adapted to engage sockets 17 secured to the inner face of the adjacent attaching member or strip 13. Thus it will be seen that by causing the sockets 17 20 to engage the different heads 16 on the reinforcing strip 15, the legs 7 may be adjusted vertically of the coat to fit the legs of the wearer and thus permit the garment to be worn by persons of different sizes.
- 25 It will here be noted that by reason of the flexible connection between the upper end of each leg 7 and the coat, the legs of the wearer may be moved in any direction, either when standing, kneeling or bending, without 30 causing the tail of the coat to wrap or bind about the legs of the wearer, or without in any manner impeding the movement of the legs when walking. It will also be noted that the legs 7 are attached to the 35 inner face of the coat at their upper ends only, the lower ends of said legs being extended below the lower edge of the coat, thus effectually to protect the trousers and prevent the same from becoming soiled.
- 40 When it is desired to use the coat in the ordinary manner, the legs 7 may be folded within the lines of the coat, by releasing the lower fastening devices 8 and 9 thereof and passing the vertical edges of the members 45 7 at said fastening devices over the adjacent attaching member or strip 13 and at the rear of the central fastening device 17' of said strip, the fastening devices 8 and 9 being subsequently pressed together so as to 50 hold the trousers legs suspended within the coat, as best shown in Fig. 3 of the drawings. If desired however, the fastening devices 8 and 9 may be omitted and the trousers legs formed of a continuous piece of 55 fabric or one or more pieces permanently united, as indicated at 7' in Fig. 4 of the drawings, which figure also shows the flexible suspension straps 12, permanently secured to both the trousers leg 7' and attaching member 13', as indicated at 18.
- 60 It will of course be understood that the guide loop or strap 14 may be secured either to the front of one of the flexible suspension straps or to the rear thereof, as indicated at 14' in Fig. 4 of the drawings.

In Figs. 5 to 8 inclusive, there is illustrated a further modification, in which the material forming the vertical edges of each trousers leg is overlapped and detachably united by suitable fastening devices 19. In this form of the device, the flexible suspension straps 12, are dispensed with and the legs suspended from the inner face of the coat by interengaging fastening devices 16' secured to the reinforcing strips 15' and tapes 10'.

In folding the leg shown in Fig. 5 of the drawings, the lower fastening device 19 is released and the ends of the material, indicated at 20, passed over the reinforcing tape 10' and downwardly between said tape and the reinforcing strip 15' on opposite sides of the central fastening device 16', the members comprising the fastening device 19 being subsequently brought together, as best shown in Figs. 7 and 8 of the drawings, this folding operation being substantially the same as the folding operation in Figs. 1 and 3 of the drawings.

It is to be noted that the members 7 of the different forms of the device, are secured to the inner face of the coat at their upper ends only, the lower ends of the members 7 being free so as to permit freedom of movement of the legs of the wearer. It will also be noted that the strip 15 not only forms a means for supporting the fastening device 16, but also serves to reinforce and strengthen the pockets 6 and to receive the direct strain or pull of the members 7 when bending or kneeling, thus effectually to prevent tearing or otherwise injuring the coat.

It will of course be understood that the legs or members 7, shown in Figs. 1 to 8 inclusive, may be entirely detached from the garment and carried in the pocket, when it is desired to use the coat in the ordinary manner, but it is preferred to fold the members 7 within the lines of the coat when not in use, so that said members will always be in position to receive the legs of the wearer when it is desired to change the character of the garment from an ordinary coat to a combination coat and trousers, this result being effected by releasing the fastening devices 8 and 9 shown in Fig. 2 of the drawings, and 19 shown in Fig. 5, and allowing the members 7 to drop until the free ends thereof project below the lower edge of the coat, as will be readily understood.

Having thus described the invention, what is claimed as new is:

1. A garment including a coat, trousers legs suspended from the inner face of the coat, attaching members secured to the coat, and intersecting flexible suspension elements permanently secured to said attaching members and detachably secured to the upper portions of the trousers legs.
2. A garment including a coat, reinforcing

strips secured to the inner face of the coat, trousers legs suspended from said coat, attaching members, intersecting flexible suspension straps forming a connection between
 5 the upper ends of the trousers legs and the adjacent attaching members, a loop secured to one of the suspension straps of each trousers leg and embracing the other strap thereof, and interengaging fastening devices carried by the attaching members and reinforcing strips, respectively.

3. A garment including a coat, reinforcing strips secured to the inner face of the coat, trousers legs suspended from the inner
 15 face of the coat at said reinforcing strips, attaching members, flexible suspension straps having their upper ends permanently secured to the attaching members and their lower ends detachably secured to the upper
 20 ends of the trousers legs, and interengaging fastening devices carried by the attaching members and reinforcing strips, respectively.

4. A garment including a coat, reinforcing strips secured to the inner face of the
 25 coat, attaching members trousers legs suspended from said attaching members and each having their vertical edges overlapped and detachably united, and interengaging fastening devices carried by the reinforcing
 30 strips and attaching members, respectively, the lower end of each trousers leg being adapted to be passed over one of said fastening devices and between the reinforcing strip and upper end of the trousers leg for holding the lower end of the trousers leg in
 35 elevated position.

5. A garment including a coat, reinforcing strips secured to the inner face of the coat, trousers legs suspended from the reinforcing strips and each formed of a strip of
 40 material, the adjacent vertical edges of which are overlapped, fastening devices for

securing the overlapped edges of each trousers leg in assembled position, the members forming one of the fastening devices on
 45 each trousers leg at the bottom thereof being adapted to be released and said trousers leg folded upon itself and passed downwardly between the upper end of said trousers leg and the adjacent reinforcing strip
 50 and the members of said fastening device united for holding the trousers leg in folded position.

6. A garment including a coat, reinforcing strips secured to the inner face of the
 55 coat, trousers legs suspended from said reinforcing strips, attaching members, intersecting flexible suspension straps permanently secured to the attaching members and detachably secured to the upper portions of the trousers legs, and interengaging fastening devices carried by the attaching members and reinforcing strips respectively.

7. A garment including a coat, attaching
 65 members, trousers legs suspended from said attaching members and each having their vertical edges overlapped and detachably united, and interengaging fastening devices carried by the inner face of the coat and the attaching members, respectively, the lower end of each trousers leg being adapted to be passed over one of said fastening devices and between the inner face of the coat and upper end of the trousers leg for holding the lower end of the trousers leg in elevated position.

In testimony whereof, we affix our signatures in presence of two witnesses.

GUSTAVE A. KURZ [L. S.]
 HARRY C. SHONTING.
